UNITED STATES PATENT OFFICE.

WILLIAM H. WILTSHERE, OF GILLESPIEVILLE, OHIO.

GRAVEL-BOTTOM FOR WAGON-BEDS.

1,270,085.

Specification of Letters Patent.

Patented June 18, 1918.

Application filed September 8, 1917. Serial No. 190,374.

To all whom it may concern:

Be it known that I, WILLIAM H. WILTSHERE, a citizen of the United States, and a resident of Gillespieville, in the county of Ross and State of Ohio, have invented a new and Improved Gravel-Bottom for Wagon-Beds, of which the following is a full, clear, and exact description.

This invention relates to wagons or the like for the conveyance of dirt, sand, gravel, asphalt or other loose commodities and has particular reference to the construction of a wagon box or body having movable planks for dumping purposes.

Among the objects of the invention is to provide an improved arrangement or construction of the body bottom whereby the movable planks are all interlocked with one another and with the side panels of the body so as to prevent independent longitudinal movement of any of said planks.

Another object of the invention is to provide improved locking means for the bottom planks of such a nature that the connection of one plank to another may be effected practically automatically subject to a final locking action of a simple part.

A still further object of the invention is to provide a wagon body for the conveyance of sand, gravel, dirt or other dry loose granular material, said body being so constructed as to prevent the lateral spreading of the side panels between the usual bolsters and stakes and whereby the danger of leakage of the commodity will be practically eliminated, and downward sagging will be prevented.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a vertical longitudinal section approximately on the line 1—1 of Fig. 2.

Fig. 2 is a bottom plan view of the wagon body and parts directly beneath the same.

Fig. 3 is a vertical transverse section on the line 3—3 of Fig. 1.

Fig. 4 is a side elevation of a detail as it would be seen from the arrow 4 of Fig. 5.

Fig. 5 is a vertical transverse sectional detail on the line 5—5 of Fig. 4; and

Fig. 6 is a detail perspective view of one of the locking plates such as are applied to the central portion of each plank, excepting the last.

Referring now more particularly to the drawings I show a wagon body comprising vertical side panels 10 and 11 supported at their lower edges upon bolsters 12 and 13 and braced in the usual way from lateral movement at their ends by standards 14 fixed to the bolsters. The body also includes end pieces or gates 15 which may be connected loosely with the side panels and held from displacement by cleats 16 or any other well known expedient, outside cleats 17 serving to prevent endwise movement of the side panels. The remainder of the body comprises a series of parallel shiftable or movable planks 18, the general object and nature of which are well understood in the art.

I now call particular attention to the interlocking devices which constitute the principal part of my invention. Fig. 6 indicates a plate 19, the main portion 20 of which is practically rectangular and is adapted to be fixed to the bottom of the central part of any one plank 18 by means of screws or other fasteners passing through suitable holes 21. The main portion of the plate 20 is provided with a longitudinal slot 22 at about the center, the width of the slot being approximately identical with the thickness of the metal of which the plate is made. At one side the plate is provided with a shank 23 terminating in its free end in an upwardly projecting lip 24, the length of which is approximately the same as the length of the slot. The shank 23 is below the plane of the main portion 20 of the plate and the length of the shank is equal to about one half of the width of the plank. This description of the plate pertains to all of the planks except the last one of the series.

A special form of plate is indicated at 25 and is provided with an upwardly projecting flange or lip 26. This plate 25 is secured to the bottom edge of the side panel 10 of the body, the lip 26 embracing the outer side of the panel 10. This special plate furthermore is provided with a shank 23 and a lip 24 which are of the same nature and for the same purpose as the corresponding features already described.

The last plank is provided with a plate 27 which corresponds substantially to the rectangular portion 20 of the standard plates 19, the shank 23 and its lip 24, however, being omitted. It will now be understood that the plates 19, 25 and 27 are so connected to the side panel 10 and planks 18 as to lie in transverse alinement across the middle portion of the body planks which are all in proper position with respect to the side panels and bolsters. It will be noted furthermore that the lip 24 of each plate in normal position of the planks will project into the slot 22 of the next plate of the series and hence so long as the last plank of the series or any portion of the series is held from endwise movement all of the previous element of the same series or portion will be locked by their respective shanks and lips.

The last plate 27 of the series is provided with a slot 22' that is the same length as those already described but adapted to receive two lips, the lip 24 of the last shank 25 on the one side and a lip 28 of a movable plate 29 shown in this instance as pivoted at 30 to the lower end or edge of a plate 31 fixed on the outer face of the side panel 11. The plate 31 is provided with a pair of ears or lugs 32 preferably struck out from the same at right angles to the plate and to these ears or lugs is secured a hanger 33 having pivoted to the lower extended end thereof at 34 a lever 35. This is a lever of the first class and is pivotally connected to the plate 29 at its inner end by means of a link 36 pivoted at one end at 37 to a lug 38 struck out from the plate 29 and at its other end 39 to the lever 35. The plate 29 is so designed as to swing upward against the bottom edge of the panel 11 bringing the lip 28 thereof into the slot 22' next to the last lip 24. The lever 35 and its link connection 36 with the plate 29 are so designed that when the handle end of the lever is swung downward the inner end of the lever swings upward toward or against the plate 29 carrying the pivot 39 past the dead center or beyond the plane common to the pivots 34 and 37. By this time, however, this action of the lever will force the lip 28 into the locking position already indicated. It follows therefore that this action of the lever will not only force the plate 29 into locking position, but will insure the safe holding of the lever in its locking position.

It will thus be seen that not only will the pivoted locking plate 29 make more secure the interlocking action between adjacent planks, but will constitute the final link of what may be termed a transverse binding chain serving to prevent all tendency of the middle portions of the side panels 10 and 11 from bulging laterally under the weight of the load and hence my construc-

tion insures that there shall be no material gap or crevice formed in any part of the bottom that would permit the load to leak through the body bottom.

When it is desired to dump the load the operator will swing the outer end of the lever 35 upward bringing the pivot link and plate down as shown in Fig. 5, where they will hang idle until the locking devices are to be operated again. At the time the binding action is relieved from the side panels and bottom planks the operator may lift and turn the last plank or the one which bears the plate 27 and likewise in turn he may lift all the other planks, dumping the load in the usual manner through the bottom of the body. After the contents of the body are dumped the planks may be put back in place readily beginning first at the right hand side of Fig. 3 putting the first plank down and sliding it endwise until the first lip 24 enters its slot. Each plank will remain in place until the succeeding planks in turn are similarly positioned and finally locked by swinging the plate 29 into the locking position indicated in Fig. 3.

I claim:

1. The herein described wagon body comprising side and end panels, movable longitudinal bottom planks filling the horizontal space between the bottom edges of the side panels, and disconnectible interlocking means coöperating with the side panels and each two adjacent planks serving to hold the planks from independent endwise movement. 100

2. The combination with a wagon body comprising side and end panels and bottom planks, of a transverse chain of disconnectible interlocking links connected to the side panels and the respective planks, whereby the planks may be readily manipulated singly when unlocked but are held from all independent movement when locked, substantially as set forth. 105

3. The combination with a wagon body comprising side panels and bottom planks filling the space between the panels, of a plate secured to the bottom face of each plank, the several plank plates being arranged in transverse alinement when the planks are in normal position, means connecting each plate with the next adjacent plate, said connecting means permitting free independent movement of the planks in succession, and means to connect the plank plates with the side panels. 110

4. The combination with a wagon body comprising side panels and a series of bottom planks between the side panels, of a plate secured to the bottom of each plank and having a slot therein, means secured to one of the side panels and coöperating with the slotted plate adjacent thereto to prevent the endwise movement of the plank bearing such adjacent plate, said slotted plate having 115

means coöperating with the next adjacent slotted plate throughout the series of planks and plates except the last, and means removably connected to the opposite side panel having interlocking coöperation with the last plate of the series substantially as set forth.

5. In a wagon body, the combination of

spaced side bars, independently movable bottom planks in said space, separable link devices connected to the several planks, and means coöperating with said link devices serving to prevent all movement of the planks endwise or laterally.

WILLIAM H. WILTSHERE.
